ABSTRACT

The invention contemplates a pressurized container, as for the containment of viscous product to be selectively dispensed, and relying on an internal piston as the means of constantly loading the product for displacement in the direction of dispensing nozzle. The base of the container is closed by a resilient plug, jammed into a converging concave formation that is so configurated, in relation to a pressure-charging and plug-inserting tool, as to assure unerring closure without charge leakage, and at the same time to have the tool universally effective in performing its function for a wide range of container sizes.

10 Claims, 4 Drawing Figures

PRESSURE OPERATED DISPENSING CONTAINER WITH SPECIAL INLET FOR A PLUG SEAL

This application is a division of my copending application, Ser. No. 305,304 now U.S. Pat. No. 3,827,212, filed Nov. 10, 1972.

This invention relates to a particular feature of pressurized-container construction at the region of pressure-charging, and to coacting tool structure and procedure having to do with pressure-charging and sealing the container.

It is an object of the invention to provide an improved construction and method of the character indicated.

A specific object is to meet the above object with tool structure which is inherently self-centering at the pressure-charging port of the container and which is universally applicable to a range of container sizes.

A general object is to achieve the above objects at reduced cost and greater efficiency than heretofore.

Other objects and various further features of novelty and invention will be pointed out or will occur to those skilled in the art from a reading of the following specification, in conjunction with the accompanying drawings. In said drawings:

FIG. 1 is a longitudinal sectional view through a pressurized container, which has been pressurized by the means and method of the invention;

FIG. 2 is a fragmentary longitudinal sectional view through cooperating container and charging-tool parts, in accordance with the invention;

FIG. 3 is a view similar to FIG. 2, to illustrate cooperating parts in a subsequent relationship; and

FIG. 4 is a view similar to FIG. 2, to illustrate a modification.

In FIG. 1, the invention is shown in application to a cylindrical pressurized container or can 10, with an integral conical top-end wall 11, and provided with a valve 12, for the dispensing of viscous product from the region 13 within the container. The valve 12 is of the variety in which a valve stem 14, is resiliently supported by an elastomeric bushing 15 and is pressed laterally in a well-known manner in order to open the valve seal and permit viscous product, which is at super-atmospheric pressure, to be expelled to the atmosphere.

The open lower end of the container body is permanently closed by an upwardly domed end wall 16, at a peripherally continuous chimed connection 17, and a resilient elastomeric plug 18 at a central opening 19 seals off the pressurized contents. Within the container, a movable piston 20 having an integral peripheral flexible seal flange 21 establishes an interior division between the viscous-product region 13 and a pressurized-gas chamber 22 beneath piston 20. As shown, a clearance A between flange 21 and the primary skirt or body 23 enables piston 20 to maintain a smooth upwardly-riding sealed division between the interior regions 13-22, as dictated by the extent to which product has been dispensed, and in spite of surface irregularities, such as dents, in the inner wall surface 10a of the container body.

FIG. 2 illustrates the relationship between the container opening 19 and a pressure-charging and sealing tool 25. In accordance with a feature of the invention, the opening 19 is at the inner end of an inwardly tapering concavity or mouth 26, the same being shown as

frusto-conical at a taper angle α to the container axis 27 and in the range of 45° to 75°, i.e., making an included angle in the range 90° to 150°, preferably about 120°. A short axial flange portion 28 provides assurance of a smoothly defined throat for opening 19, avoiding burrs or a sharp edge at the region of greatest compression of plug 18. The tool 25 is generally cylindrical, with a nozzle end having a convex tapered surface 29 which matches and therefore accurately centrally aligns with the concave taper of mouth formation 26, as shown. The interior of tool 25 includes a guide bore 30 sized to accommodate a plug element 18 in relatively unstressed condition, positioned by piston means 31, in readiness for upward displacement into plugging relation with opening 19; the tool bore tapers inwardly to a minimum extent at a discharge-exit or throat end 32, of diameter corresponding substantially to that of the throat region 28 of opening 19. It will be appreciated that, with the tool 25 fitted to mouth 26, as suggested by arrows F_o indicative of applied compressive abutment of the nozzle with respect to mouth 26, a substantially smooth and continuous passage is presented to the radially compressed plug 18, in the course of plug insertion; the plug-insertion force is suggested by arrow F_p , and a flexible platform 33 forming part of piston means 31 yields radially to permit plug 18 to be axially driven to the desired extent (FIG. 3). Prior to plug insertion, a passage 34 communicates gas under pressure to the container via the nozzle passage 32, the supply and control means therefor being schematically suggested by a heavy broken arrow 35; gas-tight connection from nozzle to container is provided by an elastomeric annulus or O-ring 36, surrounding the fit of the tapering surfaces 26-29 and sufficiently thick to be circumferentially continuously compressed between adjacent surfaces 29-16 under the force F_o .

The procedure for gas-charging the container 10 is seen to involve selection of matched concave and convex contours at 26-29, supplying a requisite quantity of pressurized gas via means 35-34 in the presence of the force F_o , and applying force F_p to drive plug 18 into home position (FIG. 3). Once the FIG. 3 position of plug 18 is reached, piston means 31 and tool 25 may be retracted, and it will be understood that the self-expanded "head" end 37 of plug 18 will sufficiently axially retain plug 18, to permit smooth and clean withdrawal. After tool withdrawal, self-expansion of the "tail" end 38 of plug 18 will expand the region of resiliently loaded circumferentially continuous seal action, from throat 28 to a substantial adjacent surface area of the mouth 26, as will be understood.

In the arrangement of FIG. 4, the parts are similar, except for the use of fitted inwardly tapering concave and convex surfaces 26'-29' which are frusto-spherical, rather than frusto-conical as in FIG. 2. The discharge-exit of the nozzle at diameter 32' again substantially conforms to that at the throat 28' of mouth formation 26'. Preferably, the arcuate extent of the convex truncation 29' slightly exceeds that of the concave truncation 26', thus permitting a small extent δ of angular self-aligning adaptation upon application of the force F_o . Other parts of FIG. 4 are as in FIG. 2 and are fully described by use of the same reference numerals, with primed notation.

The described structural relation and method will be seen to have met all stated objects, assuring an accurately centered fit of the charging tool to each suc-

sive container and without permitting any plug-fouling or plug-marring discontinuity at the throat region

32-28. There is no need for any referencing reliance on the chime 17, as in the past, and thus the invention is applicable to a wide variety of container shapes and sizes, as suggested for example by phantom outlines for a bottom wall 40 and container body 41 of substantially greater diameter than container 10. The only point in common with all such different sizes, contours and shapes, is that the mouth formation 26 (26') shall be the same, to permit service by the same charging tool 25 (25').

In a typical successful employment of the invention, the mouth 26 has an included taper angle (2α) of substantially 120° , to a throat 28 diameter of 0.140 inch and length of substantially 0.031 inch, for accommodation of a synthetic rubber plug 18 of 5/16-inch length, cut from 0.200 to 0.250 diameter stock, the latter being selected for its toughness, resilience, and cut-resistance.

While the invention has been described in detail for the preferred forms shown, it will be understood that modifications may be made without departing from the claimed invention.

What is claimed is:

1. A pressure chargeable dispensing container adapted to be sealed by a resilient cylindrical plug supplied via a plugging nozzle having a convex tapering surface, said container comprising a cylindrical body and an upwardly domed bottom closure wall with a generally central charging opening, said bottom wall and body being chime-connected, said opening being defined at the small end of an inwardly tapering and locally more sharply concave mouth formation limited to the central region of said domed closure wall and having circumferential symmetry about the opening, said mouth formation having a taper substantially matching that of the plugging nozzle, and the diameter of said opening substantially matching the exit-bore diameter of the plugging nozzle; whereby as a result of mating convex and concave surfaces, a plugging nozzle having a convex surface of taper substantially matching that of said mouth and further having an exit-bore diameter substantially matching the minimum diameter of said mouth, may be self-centering into accurate coaxial fit to and registration with the opening of said mouth, independently of diameter variations of said chime connection, so that a resilient cylindrical plug of diameter exceeding the opening diameter may be accurately inserted in the opening, with the relatively uncompressed and externally exposed end of the plug largely received in the concavity of said mouth.

2. The container of claim 1, in which the inward taper of said mouth formation is substantially conical.

3. The container of claim 2, in which the included

5

angle of the conical taper is in the range between 90° and 150° .

4. The container of claim 2, in which the included angle of the conical taper is substantially 120° .

5. The container of claim 1, in which the inward taper of said mouth formation is that defined by the frustum of a sphere centered on the axis of charging opening.

10 6. The container of claim 1, in which the axially inner end of said inward taper includes an axially extending flange, whereby a circumferentially continuous smooth throat is defined for resilient-plug reception.

15 7. A pressure-chargeable dispensing container adapted to be sealed by a resilient cylindrical plug supplied via a plugging nozzle having a convex tapering surface, said container comprising a cylindrical body and an upwardly domed bottom closure wall with a generally central charging opening, said opening being defined at the small end of an inwardly tapering and locally more sharply concave mouth formation limited to a generally central region of said closure wall and having circumferential symmetry about the opening, said mouth formation having a taper substantially matching that of the plugging nozzle, and the diameter of said opening substantially matching the exit-bore diameter of the plugging nozzle; whereby, as a result of mating convex and concave surfaces, a plugging nozzle having a convex surface of taper substantially matching that of said mouth and further having an exit-bore diameter substantially matching the minimum diameter of said mouth, may be self-centering into accurate coaxial fit to and registration with the opening of said mouth, independently of the size or configuration of said closure wall, so that a resilient cylindrical plug of diameter exceeding the opening diameter may be accurately inserted in the opening, with the relatively uncompressed and externally exposed end of the plug largely received in the concavity of said mouth.

20 8. The container of claim 7, in which said inward taper is characterized by an axially inner diameter which is approximately one-half the axially outer diameter thereof.

25 9. The container of claim 8, and including a resilient plug of unstressed diameter approximating said axially outer diameter compressively retained in the opening, with the axially outer end of said plug largely contained within said inwardly tapering formation.

30 10. The container of claim 8, and including a resilient plug of unstressed diameter approximating said axially outer diameter compressively retained in the opening, with the axially outer end of said plug in compressed circumferentially continuous contact with the opening and with a substantial adjacent annular region of said concave mouth formation.
